UNITED STATES PATENT OFFICE.

THOMAS S. STEVENS, OF TOPEKA, KANSAS, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,152,448.

Specification of Letters Patent.

Patented Sept. 7, 1915.

Application filed June 7, 1912. Serial No. 702,209.

To all whom it may concern:

Be it known that I, THOMAS S. STEVENS, a citizen of the United States, residing at Topeka, in the county of Shawnee and State of Kansas, have invented certain new and useful Improvements in Railway Signaling, of which the following is a specification.

My invention relates to the automatic control of the supply of energy to certain devices whereby the consumption of energy by such devices may be regulated.

More particularly my invention relates to the automatic control of lamps or other devices consuming energy in a railway signaling system, the control being such that as a car or train proceeds along the railway sufficient operating current is supplied to said device or devices in advance of the car or train.

I will describe my invention as applied to a railway signaling system and specifically to the automatic control of the current supply to the signal lamps employed in such system as the train proceeds along the rail-way.

In the accompanying drawing Figure 1. is a diagrammatic view of a portion of a railway track having applied thereto a signaling system embodying my invention. Figs. 2 and 3 are similar views but illustrating modifications each embodying my invention.

Similar reference characters designate corresponding parts in all of the figures.

In the practice of my invention I provide means included in each track circuit which as a car or train enters the track circuit becomes operative to control the supply of current to an energy consuming device such as a signal lamp, located in advance of the car or train. Therefore by means of my invention, the signal lamps in a signaling system may be usually extinguished, and the lamp for a signal be illuminated only when a car or train is approaching that signal, and hence maximum economy in the operation of the signal lamps is obtained. The same results of course may be obtained with other energy consuming devices employed in the signaling system.

Referring now to the drawings, in each of the figures A, B and C designate three successive block sections of a railway track,

which sections are protected respectively by railway signals S, S¹ and S². Each of these signals as here shown comprises a semaphore for daylight indications and an electric lamp L, L¹ or L² for night indications. The block sections are provided with track circuits; as here shown one track circuit is provided for each block section although it is understood that I do not limit myself to this particular number. As usual, each track circuit comprises a source of signaling current, the track rails of the block section or portions of them, and a track relay. As here shown the sources of signaling current are transformers T, T¹, T², etc., the secondary windings 10, 11 and 12 of which are connected with the track rails of the block sections. The primary windings of these transformers T, T¹, T², etc., are connected with transmission conductors 13 which are supplied with an alternating current from any suitable source, which source is not shown in the drawings.

R, R¹ and R², are track relays which may be of any desired type operable by an alternating signaling current. They are of the induction motor type each comprising a winding connected with the track rails, and a short-circuited member which actuates contacts for the control of the signal for the corresponding block section. For example, the contacts operated by relay R¹ control the circuit for signal S¹, the source of current for which circuit is another secondary winding 14 of transformer T¹. The circuits for signals S and S² are similarly controlled by track relays R and R² respectively.

Included in each track circuit between the source of current and the track rails are means for the control of the supply of current to the signal lamp for the next succeeding block section. I will now describe three forms of means for such control, referring separately to each of the views.

Referring to Fig. 1, the means here shown is in the form of a relay, 17, 18, 19, designate such relays, each comprising a winding which is included in one lead between the source of current and a track rail, and an armature which opens and closes a lamp circuit. Each signal lamp is provided with a

circuit which includes a source of current and a contact or contacts which are opened and closed by the armature of the relay device for the preceding track circuit. For example, the circuit for lamp L^1 includes a secondary winding 20 of transformer T^1 and a contact or contacts 21 which are controlled by the relay 18. Each relay, 17, 18, 19, etc., is so adjusted that when the rails 10 of the track circuit are not occupied by a car or train, the current which flows in the winding of the relay is not sufficient to have it attract its armature to close the contact 21; but when the rails of the track circuit 15 are bridged by a car or train, thereby shunting out the resistance of the track winding of relay R , the increased current drawn from the source 10, 11 or 12 flowing through the winding of the relay is sufficient to have 20 the relay attract its armature to close the contact 21. Hence when block section A is occupied by a car or train as indicated by the wheels and axle W, lamp L^1 of signal S^1 becomes illuminated. Lamps L and L^2 are 25 controlled respectively by relays 17 and 19 in a similar manner.

Referring now to Fig. 2, a lamp controlling means is here shown comprising a transformer 22, 23 or 24, whose primary winding 30 is included in a track circuit and whose secondary winding is connected with a relay 25, 26 or 27. Each relay 25, 26 and 27 controls a contact or contacts included in the lamp circuit like that illustrated in Fig. 1. 35 The adjustment of the parts is such that when the block section A is unoccupied, the current in the primary of transformer 23 is insufficient to cause relay 26 to be energized, but that when block section A is occupied by a car or train indicated by the wheels and axle W, the increased current in the primary of transformer 23 causes relay 26 to be energized so that its armature closes the circuit for lamp L^1 . The control of signal lamps L and L^2 by transformers 22 and 24 and relays 25 and 27 is similar to that just explained for lamp L^1 .

Referring now to Fig. 3, the lamp controlling means here shown is similar to that 50 shown in Fig. 2, except that the signal lamps are energized directly from the secondaries of transformers 22, 23, and 24 respectively, instead of through a relay device. For example, lamp L^1 is connected directly 55 in circuit with the secondary of transformer 23. The parts are so adjusted that when block section A is unoccupied, the current in the primary of transformer 23 is insufficient to illuminate lamp L^1 , or is at the most 60 sufficient to illuminate the lamp only faintly, but that when block section A is occupied by a car or train as indicated by the wheels and axle W, the current drawn from the source 11 is then sufficient to cause the full 65 illumination of lamp L^1 .

Although I have herein shown and described only three forms of apparatus and circuits embodying my invention, it is understood that various changes and modifications may be made therein within the scope 70 of the appended claims without departing from the spirit and scope of my invention.

Having thus described my invention, what I claim is:—

1. In combination, a plurality of successive sections of a railway track; track circuits for the sections each including a source of energy and a track relay connected with the rails of a section; signals for the sections controlled by said track relays, lamps 80 for the signals for giving signal indications at night, a second relay for each section receiving energy from the connection between the source of energy and a rail of the section, and a circuit for a lamp of each signal, said lamp circuit being controlled by said second relay for the section in the rear. 85

2. In combination, a plurality of successive sections of a railway track; track circuits for the sections each including a source 90 of alternating current and a track relay connected with the rails of a section; signals for the sections controlled by said track relays, lamps for the signals for giving signal indications at night, a transformer for each 95 section whose primary receives current from the connection between the source of current and one rail of the section and a circuit for a lamp of each signal, said lamp circuit being controlled by the secondary of the transformer for the section in the rear. 100

3. In combination, a railway track divided into a plurality of successive sections, track circuits for the sections each comprising a source of current connected with the rails 105 and a track relay also connected with the rails, signals for the sections controlled by said relays, lamps for the signals for giving signal indications at night, and means for each section receiving current from the connection of the source of current with a rail of the section for controlling the lamp of the signal for the section next in advance. 110

4. In combination, a plurality of successive sections of a railway track, means for each section for supplying signaling current to the rails of the section, a relay for each section receiving current from the rails of the section, signals for the sections controlled by said relays, lamps for the signals 115 for giving signal indications at night, and means for each section receiving current from the said current supplying means for the section for controlling the lamp of the signal for the section next in advance. 120

5. In a signal system, a plurality of block sections, each block section including a closed track circuit having connected in series therein a source of current and an electrical device of high resistance, said elec- 125 trical device 130

trical device being arranged to be short-circuited when a train enters the block section including the circuit containing said electrical device, and thereby causing an increased flow of current from the source of current contained in said circuit, a signal device for each of the said block sections, and electrical means whereby upon said in-

crease of current said signal device will be illuminated.

In testimony whereof I affix my signature in presence of two witnesses.

THOMAS S. STEVENS.
